APPARATUS FOR LOADING SHEATH WIRE
HEATING UNITS PROVIDED WITH A
SHEATH

Albert H. Simmons, Wheaton, Ill., assignor to Edison General Electric Appliance Company, Inc., a corporation of New York

Application November 3, 1934, Serial No. 751,333

16 Claims. (Cl. 18—5)

This invention relates to electric heating units, more particularly to electric heating units of the sheathed type, and it has for its object the provision of improved apparatus for making heating units of this character.

This invention has particular application to electric heating units wherein a resistance conductor is encased by a sheath and is embedded in and held in spaced relation with the sheath by means of an electrically insulating, heat refractory and conducting material, such as powdered magnesium oxide. One electric heating unit of this type is described and claimed in United States Patent No. 1,367,341 to C. C. Abbott, dated February 1, 1921.

This invention contemplates the provision of improved apparatus for loading a sheath with insulating material so as to embed and hold the resistance conductor in spaced relation with reference to the sheath, in a simple, reliable and efficient manner and with greater rapidity than has been possible with the apparatus heretofore known.

In accordance with this invention, suitable means are provided for holding the sheath in a substantially upright position, and additional means are provided for holding the terminals of the resistance element, which are connected to the ends of the conductor, in proper relation to the sheath, generally in the vertical center line of the sheath. Suitable apparatus is provided for feeding to the sheath the powdered magnesium oxide at a predetermined regulated rate. A centering device is arranged to be inserted in the sheath to hold the portions of the resistance element between the terminals in the center line of the sheath while the sheath is being loaded. The centering device is controlled to move upwardly in the sheath as the sheath is being filled with the insulating material so that the level of the insulating material is always just below and follows the centering device. In addition to this, a suitable vibratory device is provided for applying to the sheath intermittent impacting blows to settle the insulating material within the sheath while it is being filled. The vibratory device is controlled to move upwardly along the walls of the sheath at a regulated rate so as to apply the blows always substantially at the rising level of the insulating material.

It is contemplated that the insulating feeding means, centering device and the vibratory device all will be controlled by a single control lever, which is manually operable to start the loading operation, and it is further contemplated that

these elements will be automatically controlled to stop the loading operation when the sheath has been filled.

For a more complete understanding of this invention, reference should be had to the accompanying drawings, in which Fig. 1 is a vertical side elevation of apparatus for loading a sheathed heating unit arranged in accordance with this invention; Fig. 2 is a view similar to Fig. 1, but showing certain elements of the mechanism in different operative positions; Fig. 3 is an enlarged front elevation of a portion of the mechanism shown in Figs. 1 and 2; Fig. 4 is a side elevation of the mechanism of Fig. 3; Fig. 5 is a sectional view taken through the line 5—5 of Fig. 3 and 15 looking in the direction of the arrows; Fig. 6 is a fragmentary sectional view taken through a portion of the apparatus shown in Fig. 5; Fig. 7 is a fragmentary sectional view taken through the line 7—7 of Fig. 6 and looking in the direction of 20 the arrows; Fig. 8 is a plan view of a vibratory device used in the loading apparatus of Figs. 1 and 2; Fig. 9 is a view similar to Fig. 8, but illustrating certain of the elements of the vibratory device in different operative positions; Fig. 10 is 25 an enlarged elevation in section taken through the line 10—10 of Fig. 8 and looking in the direction of the arrows; Fig. 11 is an enlarged fragmentary view, mainly in section, of certain portions of the apparatus shown in Figs. 1 and 2; Fig. 12 is an 30 enlarged elevation, partly in section, of a portion of the apparatus shown in Figs. 1 and 2; and Fig. 13 is an elevation, partly in section, of a sheathed 35 electric heating unit of the type to which this invention is particularly applicable.

Referring to the drawings, this invention has been illustrated in one form as applied to electric heating units of the sheathed type, such as described and claimed in the above-mentioned Abbott Patent No. 1,367,341. Referring to Fig. 13, 40 a heating unit of this type has been illustrated. As shown in this figure, the heating unit comprises a helical resistance element 10 encased by a metallic sheath 11. Suitable terminals 12 are mechanically and electrically connected to the 45 ends of the resistance element 10. The resistance conductor is threaded on the terminals as shown and as fully described in the U. S. Patent No. 1,494,938 to C. C. Abbott, dated May 30, 1924. The resistance conductor 10 is embedded in and 50 held in spaced relation with reference to the sheath 11 by a suitable powdered heat refractory and conducting, electrically insulating material 13, such as powdered magnesium oxide. The magnesium oxide functions to hold the resistance 55

element 10 substantially in the longitudinal center line of the sheath, and to conduct heat from the resistance element to the sheath. The inner ends of the terminals 12 are also embedded in the insulating material 13, as shown, and are insulated from the sheath 11 and held in spaced relation with it by means of the powdered insulating material.

The apparatus for loading the sheath comprises means for holding it in an upright position, as shown in Figs. 1, 2, 11 and 12, and for holding the resistance element 10 and its terminals 12 in the positions they should occupy with reference to the walls of the sheath, in this case, in the vertical center line of the sheath. The upper end of the sheath is supported by means of a metallic frame 14 (Figs. 1, 2, 5 and 11). The frame 14, as shown, is provided with a metallic insert 15 which has a recess 16 provided in it to receive the upper end of the sheath, as more clearly shown in Fig. 11. This insert is detachably secured to the frame in any suitable manner, as by means of set screws (not shown). The lower end of the sheath is supported by a pedestal 17 (Fig. 12) which comprises a cylindrical member 18 supported in an upright position and within which is fitted a rod 19 that carries on its upper end a base or bearing 20 for the lower end of the sheath. This member 20, as shown, has a curved upper surface upon which the lower end of the sheath rests. The plunger or rod 19 is fitted within the cylinder 18 and rests upon a compression spring 20a arranged within the cylinder. This spring biases the sheath upwardly into the recess 16, as shown in Fig. 11. The rod 19, as shown, is passed through an opening in the base 20 with enough of the rod projecting above to form a centering means for the lower end of the sheath 11. If there is a heating unit of a materially different length to be filled, the base 20 will be provided with a rod 19 of proper length.

The terminal 12 at the lower end of the sheath is supported in its central position with reference to the sheath by means of a suitable washer 12a (Fig. 12) attached to the terminal. This washer is received in a recess 21 provided for it in the lower end of the sheath, as clearly shown in Fig. 12. The washer 12a is a solid washer, and therefore, in addition to holding the terminal 12 central of the sheath, functions to close the lower end of the sheath.

The upper terminal 12 is secured in fixed relation with reference to the sheath, in this case in the center line of the sheath, by means of a rod 23, to the lower end of which is attached a hook 24 which is arranged to receive a member 25 of T-shape secured to the upper end of the terminal 12, as shown in Fig. 11. The upper end of the rod 23 is rigidly secured to a retaining member 26. Set screws 27 are provided to secure the rod to the retainer. The retaining member 26, as will be pointed out in greater detail hereinafter is rigidly secured in a stationary position to a rigid portion of the apparatus.

The metallic frame 14 is secured to a pair of upright supporting rods 28 which are arranged in parallel spaced relation, as shown in Fig. 3. The rods are rigidly secured at their upper and lower ends in spaced relation. These rods rigidly support the rod retainer 26.

The metallic frame 14 is slidably mounted upon the rods 28, the frame 14 being provided with bearings 29 arranged to slide upon the rods.

Suitable set screws 30 are provided for holding the frame 14 in its adjusted position on the rods.

The frame 14 carries suitable means for feeding the powdered insulating material 13 at a regulated rate to the metallic sheath 11 while it is supported in its upright position. For this purpose, the frame 14 carries a suitable chute 31 (Figs. 3 to 6 and 11) which directs the powdered insulating material into the upper end of the sheath. As shown, the metallic member 15 carried by the frame 14 is provided with a conical bore 32 which terminates in an opening 33 positioned directly above the open upper end of the sheath, as clearly shown in Fig. 11 of the drawings. It is through this bore 32 and opening 33 that the chute feeds into the sheath. Moreover, it will be observed that the terminal 12 projects through the opening 33 and bore 32 for engagement with the supporting rod 23.

The insulating material 13 is fed to the sheath 11 from a suitable hopper 34 (Figs. 1 and 2). Interposed between the hopper 34 and the chute 31 is a suitable feeding device arranged to feed the insulating material from the hopper into chute at a predetermined regulated rate. The feeding means comprises a suitable conveyor 35 (Figs. 5 and 6). The conveyor, as shown, comprises a cylindrical member 36 arranged to rotate on a horizontal axis and provided with a plurality of feeding blades 37 on its outer surface. The member 36 with its blades 37 is arranged to rotate in a cylindrical housing 38 which at its upper left-hand end, as viewed in Fig. 6, communicates with the hopper 34 by means of a conduit 39 and at its lower right-hand end communicates with the chute 31 through a port 40. The conveyor is arranged to rotate in a counter-clockwise direction, as viewed in Fig. 5, and when thus rotated to engage the powder which is fed to its left-hand end from the hopper 34 and gradually convey it to the right-hand end where the port 40 is located. The angular set of the blades 37 at their right-hand end are straightened out as shown so as to lie substantially parallel with the axis of rotation of the cylinder 36. This arrangement of the blades prevents crowding or piling up of the powder above the port 40, and insures a gradual regulated movement of the powder from the hopper 34 to the chute 31. Furthermore, in order that the rate of powder flow through the feeding chamber 38 will be independent of the quantity of powder in the hopper, the hopper is not set directly over the intake of the cylinder 38, as clearly shown in Figs. 1 and 2. That is, the hopper is located off of the end of the cylinder 38 as shown, and the conduit 39 is given an angular shape to connect the hopper with the conveyor. A suitable manually operable shut-off valve 29a (Fig. 5) is provided in this conduit 39.

The size of the port 40 communicating with the chute is controlled by means of a slide valve 41, the position of which is controlled by a knob 42. As shown (Fig. 5), the knob 42 is provided with a flange 43 which is received in a recess 44 provided for it in the valve 41. The knob 42 has a screw threaded engagement with the frame 14 so that by adjusting the position of the knob in the frame, the position of the valve is adjusted. The valve, as shown clearly in Figs. 5 and 6, is provided with an aperture 45 which registers with the port 40. The adjustment of the valve therefore controls the effective opening of the port 40.

In order to stop the flow of powder from the

feeding cylinder, the chute 31 is mounted upon a carriage 46 for movement from its operative position shown in full lines in Fig. 5 to an inoperative position shown in dot-dash lines in this figure. 5 When the hopper is moved from its operative position to its inoperative position, the carriage 46 will move over to close the port 40.

The chute 31 is biased to its inoperative position by means of a compression spring 47 (Figs. 10 4 and 5) interposed between the feeding cylinder 38 and an abutment 48 carried by the carriage 46. A stop 48a is provided to limit the movement of the abutment 48 from the cylinder. The chute 31 is moved from its inoperative to its operative 15 position against the bias of the spring 47 by means of an operating lever 49 which is mechanically connected to rotate a shaft 50 that is journalled in bearings 59a carried by the frame 14. Also secured to the shaft 50 is a crank arm 14. Also secured to the shaft 50 is a crank arm 20 51 which is secured to the carriage 46 by means of a link 52. It will be observed that when the lever 49 is moved in a counterclockwise direction, as viewed in Figs. 1, 2, 4 and 5, it will function to move the arm 51 in the same direction and 25 thereby move the chute from its inoperative to its operative position. The chute is locked in the operative position by means of a latch 53 pivotally mounted upon a pin 54 and provided 30 with a detent 55 arranged to engage a pin 56 carried by the carriage 46. The latch 53 is biased by gravity in a clockwise direction, as viewed in Figs. 4 and 5. It will be observed in view of the foregoing that when the lever 49 is operated to move the chute from its inoperative to its operative 35 position, the latch 53 will automatically move to engage the pin 56 to lock the chute in the operative position against the force of its spring 47. It will also be observed that when the latch 53 is moved to its position shown in Figs. 4 and 5 40 to release the pin 56, the spring can then function to return the chute to its inoperative position and thereby automatically shut off the flow of insulating material from the feed cylinder 38 to the sheath 11. The latch is provided with a 45 finger seat 53a whereby the latch can be manually operated to release the carriage 46. Supported by the frame 14 is a receptacle 56a (Fig. 5) positioned to receive any insulating material that might be in the chute when it is moved to its 50 inoperative position.

The conveyor 35 is rotated by an operating shaft 57 mounted in bearings 57a carried by the frame 14. This shaft is driven by a gear 57b, which in turn is driven through a clutch 58. The clutch 58 comprises a driving member 59, and a driven member 60 which is secured to the shaft 57 by means of a set screw 61. The driving member 59 is provided with a collar 62 (Fig. 6) which is arranged about a reduced portion 63 of the driven member 60, as clearly shown in Figs. 6 and 7. A plurality of substantially semi-circular recesses 64 are provided in the inner wall of the flange 62 at spaced intervals about the periphery of the reduced portion 63. The driven member 65 65 of the clutch carries a shaft 65 (Figs. 4 and 7), which is arranged to operate on an axis lying substantially in the periphery of the reduced portion 63. The shaft 65 is provided with a portion 65a (Fig. 7) of substantially semi-circular cross-section received in a semi-circular seat 65b in the member 60, and which is arranged when in the dotted line position shown in Fig. 7 to complete the periphery of the portion 60. However, 70 when the shaft is moved from this position to

its full line position shown in Fig. 7, the semi-circular portion 65a will move into one of the recesses 64 provided in the driving member 59, as shown, and thereby mechanically lock the driving and driven members together, whereby 5 the shaft 57 and the conveyor 35 are caused to rotate with the gear 57b.

The shaft 65 is controlled by a lever 66 which is arranged to move the shaft between its dotted and full line positions shown in Fig. 7. The position of the lever 66 is controlled by the lever 49. For this purpose, the shaft 50 carries a lever or stop 67 which is arranged when the lever 49 is in its dotted line position shown in Fig. 1 to engage the lever 66 to hold it in its position shown in Fig. 1 which corresponds to the dotted line position of the lever shown in Fig. 7. When the lever 49 is moved from its solid line position in Fig. 1 to its dotted line position in this figure, that is, its full line position, shown in Figs. 2 and 4, the stop 67 is moved to disengage the lever 66 which thereupon is permitted to move to its full line position shown in Fig. 7 thereby effecting the engagement of the clutch. The lever 66 is moved to this full line position by means of a compression spring 68. Thus, when the lever 49 is moved to its position, shown in Figs. 2 and 4, the clutch will be engaged. When the lever 49 is operated to return to its full line position in Fig. 1, the stop or lever 67 will be moved to its position shown in this figure so that it will engage the lever 66 and return it to its dotted line position shown in Fig. 7 to thereby disengage the clutch, whereby the conveyor 35 will be instantly disengaged from its driving gear 57. 35

The clutch members are driven by the gear 57b in a counter-clockwise direction, as viewed in Figs. 1, 2 and 4. This driving gear 57b for the clutch is driven by means of a gear 69. The gear 69 is driven by means of a shaft 70 journalled in 40 bearings 70a carried by the frame 14, and which may be extended to drive the corresponding gears 69 of other machines (not shown) which will be identical with the one being described and arranged in a bank with it. 45

It will be observed, in view of the foregoing description, that when the lever 49 is moved from its full line position shown in Fig. 1 to its dotted line position of this figure, that is, its full line position of Figs. 2 and 4, the clutch 58 will be 50 caused to engage the gear 57b with the conveyor 35, whereby the latter will be connected to the driving shaft 70, and the chute 31 will be operated from its inoperative position of Fig. 5 to its operative position of this figure, and in which 55 position it will be locked by the latch 53 where it will remain until the latch 53 is operated to disengage the pin 56, and the lever 49 operated to return it to its inoperative position. In other words, the operation of the lever 49 from its position in Fig. 1 to its positions in Figs. 2 and 4 will start the feeding of powdered insulating material from the hopper 34 into the sheath 11. 60

As the powdered insulating material is fed into the sheath, the level of the insulating material 65 within the sheath will of course gradually rise. Suitable means are provided for holding the portions of the resistance conductor 10 lying between the terminals 12 central of the sheath while it is being loaded with the insulating material. For 70 this purpose, a suitable centralizing device 11 is provided. The centralizing device comprises a core 72 (Fig. 11) which is provided on its periphery with a plurality of spaced vertical ribs 73 arranged to engage the inner walls of the sheath 75.

and position the core 72 relative to the sheath, while the spaces between the ribs provide for the flow of insulating material from the upper end of the sheath to its lower portion below the 5 spacer. The core 72 is provided with a centrally arranged aperture 74 which is just slightly larger than the external diameter of the helical coil 10 so that that portion of the coil lying within the spacer is held central with reference to the sheath. 10 It is contemplated that the spacer 72 will be drawn upwardly in the sheath at approximately the same rate that the level of the insulating material within the sheath rises as it is being fed to the sheath so that the succeeding portions of 15 the resistance conductor are held central of the sheath until they are substantially embedded by the insulating material which thereafter will maintain the portions central within the sheath.

The spacer 71 is drawn upwardly in the tube by 20 means of a tubular member 72a which is secured at its lower end to the spacer and at its upper end to a suitable operating arm 75. The arm 75, as will be pointed out in greater detail hereinafter, is operated by means of a feed screw 76 25 which is driven at a constant speed through a suitable gear reduction mechanism 76a. The gearing 76a is driven by any suitable driving means such as an electric motor (not shown). The tube at its upper end is directly connected 30 to a sleeve 77 which in turn is connected to a yoke 78 carried by the arm 75 by means of spherical members 79. As shown, the spherical members 79 are mounted in passageways 80 provided for them in the yoke 78, and are received in 35 semi-circular recesses or seats 81 provided for them in the sleeve 77. The balls 79 are forced into the recesses 81 by means of compression springs 82. The balls and recesses provide a releasable connection between the yoke 78 and the 40 centralizer 71 so that in the event that the load imposed upon the centralizer attains a predetermined maximum, the centralizer will be released from the yoke. For example, this maximum load may be encountered in case the centralizer becomes wedged or otherwise locked in 45 the sheath 11. The tube 72a where it leaves the sheath 11 is maintained central with reference to the sheath, that is, is held so that its vertical axis is coincident with the vertical axis of the sheath, 50 by means of a sleeve 83 (Fig. 11) secured to the frame 14.

Suitable means are provided for applying to the sheath a plurality of intermittent impacting blows applied always substantially at the rising 55 level of the insulating material within the sheath, which as previously pointed out, lies just below the position of the centralizer 71. The vibrator comprises a U-shaped hammer 84 (Figs. 1, 2, 8, 9, and 11) arranged to embrace the sheath 11. The span of the legs of the U, as shown in Figs. 60 8 and 9, is somewhat greater than is the external diameter of the sheath so that when the hammer is rapidly reciprocated or vibrated, the legs will engage opposite sides of the sheath with intermittent impacting blows. The hammer 84 is operated by a rod 85 which is driven by means of any suitable vibrating mechanism 86. The vibrating mechanism has not been illustrated in detail, for any suitable mechanism may be used, 65 and the details of this mechanism form no part of the present invention. The hammer 84, together with its vibrating mechanism 86, are mounted upon a suitable carriage 87 (Figs. 8 and 9) which is provided with bearings 88 slidably 70 received by the upright rods 28.

Carried by the frame 87 is a suitable split nut 89 (Figs. 8, 9 and 10) which has two halves 89a and 89b. When the halves of these nuts are moved to engage the screw 76, as shown in Fig. 10, the frame 87, together with the hammer 84, 5 will be mechanically connected with the screw and will be elevated by the screw as it rotates. The nut segments 89a and 89b are controlled by means of levers 90 pivotally mounted to the frame 87, as shown in Figs. 8 and 9. The levers 90 are operated by means of a lever 91 pivotally mounted upon a pin 92 carried by the frame 87. The lever 91 is mechanically connected to a pair of links 93 which are connected at one end, as shown, to the levers 90, and at their opposite ends 10 to the lever 91 through the medium of a pin 94. This pin is arranged to reciprocate in a slot 95 provided for it in the frame 87. The levers 90 15 are mechanically connected together at their upper ends by means of a tension spring 96 which functions to bias the levers to their positions shown in Fig. 9 and the nut portions 89a and 89b in their disengaged positions. When the levers 90 are operated from their positions shown in Fig. 9 to their positions shown in Fig. 8, by the 20 operation of the lever 91 from its position shown in Fig. 9 to its position shown in Fig. 8 the levers move the nut segments to engage the screw 76. It will be observed that when the lever 91 has 25 thus been operated, the links 93 will lie slightly 30 below a straight line connecting the points of attachment between levers 90 and links 93, and therefore, the spring 96 will function to hold the nut segments in engagement with the screw 35 76. (Figs. 8 and 10) until this position of the links 35 is broken by the lever 91.

The yoke 75 supporting the centralizer 71 is mechanically connected to the frame 87 to be moved with it by means of a cylinder 97 surrounding the screw 76. This cylinder at its lower end 40 is rigidly secured to the frame 87, as shown in Fig. 10, while its upper end is mechanically connected with the yoke 75, as shown in Fig. 11. In view of this arrangement, the centralizer 71 is elevated in the sheath 11 at the same rate as is 45 the member 84 elevated on the exterior of the sheath. The weights of the centralizer, and its supporting rod 23, together with those of the vibrator mechanism 86, split nut assembly 89, the tube 97 and the yoke 75 are counterbalanced 50 by means of a weight 97a connected with the yoke 75 by means of a cable 97b, as shown in Figs. 1 and 2. This cable passes over pulleys 97c.

The lever 49 is operated from its position shown in Fig. 1 to its position shown in Figs. 2 and 4 55 to start the feeding mechanism, and the lever 91 is operated from its position shown in Fig. 9 to its position shown in Fig. 8 to lock the carriage to the screw 76 by means of a lever 98. This lever 98, as shown, is pivotally mounted 60 upon a suitable stud 99 (Figs. 3 and 4) which in turn is carried by the frame 14. The lever 98 is of bell crank form, and, as shown, is fulcrumed to the stud 99 substantially at its apex. One arm 98a of the bell crank 98 is pivotally connected to a parallel bar 100, while the other arm 98b of the lever 98 is connected with a handle 101. The lower end of the parallel bar 100 is pivotally connected to a link 102 which in turn is pivotally connected to an upright rigid stand- 70 ard 103.

The arm 98a of the bell crank 98 is not connected directly to the extreme upper end of the parallel bar 100 but, as shown in the drawings, is connected to the bar somewhat below its 75

upper end. The parallel bar 100 is so arranged that when the handle 101 is operated to move the lever 98 from its full line position shown in Fig. 1 in a counter-clockwise direction through 5 90° to its position shown in Figs. 2 and 4, the upper end of the parallel bar 100 will engage the lever 49 to move it from its position shown in Fig. 1 to its position shown in Figs. 2 and 4. This operation of the lever 49, as has been pointed 10 out previously in detail, will connect the feeding conveyor 35 to its driving gear 57b and at the same time will operate the chute 31 from its inoperative to its operative position. As shown, the parallel bar 100 carries on its upper end an 15 adjustable stud 100a to compensate for wear and for slight inaccuracies of manufacture.

Furthermore, this operation of the parallel bar from its position shown in Fig. 1 to its position shown in Fig. 2 will effect the engagement of the 20 split nut 89 carried by the frame 87 and its operating screw 76. That is, the bar when thus moved, will engage the lever 91 to move it from its position in Fig. 9 to its position in Fig. 8 and thereby cause engagement of the split nut with 25 the screw 76.

Therefore, when the handle 101 is moved from its position of Fig. 1 to its position of Fig. 2, it will have effected the feed of the powdered insulating material from the hopper 34 to the 30 sheath 11 at a regulated rate, and further, will have mechanically connected the centralizer 71 and the vibratory device 86 to the screw 76 which will elevate them at a regulated rate, as has been pointed out previously.

35 It is contemplated that when the sheath 11 has been filled with the insulating material, the lever 91 will be automatically operated to disconnect the vibratory device and the centralizing device from the operating screw 76, and that the lever 49 will be operated to its position shown in Fig. 1, which, as pointed out previously, will effect the disengagement of the clutch between the driving gear 57b and the conveyer 35. The lever 91 is thus automatically operated by means 40 of a cam 104 (Figs. 4, 8 and 9) with which the lever 91 is arranged to become engaged when the frame 87 carrying the vibrator is moved upwardly from its position shown in Fig. 1 to its position shown in Fig. 2 wherein the hammer is substantially at the upper end of the sheath 11. The lever 91, as shown in Figs. 8 and 9, is provided with an extension 91a which carries an adjustable stud or nut 92 positioned so that when the carriage 81 arrives at its upper position shown 50 in Fig. 2, the stud 92 will engage the cam 104 to break the toggle formed of the links 93, as shown in Fig. 8, whereby these members are drawn together by means of the tension spring 96 to occupy the positions shown in Fig. 9. This operation 55 releases the split nut from the driving screw and thereby releases the centralizing device and the vibratory device. These devices may at the proper time be returned manually to their lower positions shown in Fig. 1.

60 65 Simultaneously with this release of the vibratory device and centering device, the latch 53 is operated to release the chute 31 so that it can return to its dotted line inoperative position (Fig. 5) under the influence of its compression spring.

70 67 For this purpose, the frame 87 carries an upright pin 105 (Figs. 3 and 4) which is arranged to engage the latch 53 to release the chute substantially at the same instant of time that the cam 104 engages the lever 91 to disengage the 75 split nut from the screw 76 to operate the paral-

lel bar 100 to release the lever 49. When the latch is released, the lever 49 is, of course, permitted to return to its position of Fig. 1 from its positions of Figs. 2 and 4. This operation, as pointed out previously, moves the stop 67 into 5 such a position that it will engage the lever 66 of the clutch 58 thereby disengaging the driving gear 57b from the conveyer 36.

In making an electric heating unit using the apparatus of this invention, it will be understood 10 that the terminals 12 (Fig. 13) will be secured to the resistance conductor 10 in the manner previously described, and then the resistance conductor, together with the terminals, will be threaded through the metallic sheath 11. It will 15 also be understood that the lower terminal 12 will be provided with a washer 12a which is fitted within the recess 21 of the sheath so as to close the lower end of the sheath, and further, so as to anchor and center the lower terminal 12 20 with reference to the sheath. The lower end of the sheath will then be placed on the base 20. Then the upper terminal 12 will be mechanically connected with the rod 23, whereby it is held in the center line of the sheath. The sheath may 25 be pushed downwardly against the force of the spring 20a to facilitate the connection between the upper terminal and the rod 23. The centralizer 71 which will have been positioned above the terminal 12 during this operation will then 30 be lowered by hand and at the same time the vibratory device 86 will be lowered to its position shown in Fig. 1.

Then the lever 101 will be moved from its position shown in Fig. 1 to its position shown in 35 Fig. 2. This operation will mechanically connect the split nut 89 with the operating screw 76, whereby the vibratory device 86 and centralizing device 71 will be moved upwardly at a regulated rate by the screw. Simultaneously with 40 the engagement of the nut 89 with the screw 76, the lever 49 will be operated to its positions of Figs. 2 and 4 by the bar 100 to effect the engagement of the clutch 58, whereby the feeding device 35 will be operated, and to move the chute 45 31 to its operative position to permit insulating material fed to it to flow to the tube 11. The chute and lever 49 will be locked in their operative positions of Figs. 2 and 4 by the latch 53. The lever 101 is released immediately after it has 50 thus been operated to start the feeding operation. As the level of the insulating material within the sheath rises, the centralizing device 71 will rise just before it and the vibratory device will be elevated so that the hammer 84 will 55 intermittently apply blows to the sheath substantially at the level of the material so as to constantly settle it within the sheath while the sheath is being filled. When the sheath has been filled the cam 104 will engage the lever 91 to 60 operate it to disengage the nut 89 from the screw 76 and thereby stop the centralizing and vibratory devices. Simultaneously the pin 105 will operate the latch 53 to release the lever 49, which thereupon will move to its position shown in Fig. 65 1. This operation disengages the clutch 58 and moves the chute 31 to its inoperative position to stop the flow of powder from the chute to the tube 11.

If at any time it is desired to stop the feed of 70 the insulating material to the sheath 11 while the machine is operating to fill the sheath, it is merely necessary to manually depress the part 53a of the latch 53 to release the chute 31 and thereby permit it to move under the influence of 75

the spring 47 to shut off the flow of insulating material to the sheath 44, and permit the lever 49 to effect the disengagement of the clutch 58.

- 5 If at any time it is desired to stop the feed of the centralizing device 71 and the vibratory device 86 it is merely necessary to grasp the lever 91 and move it from its position of Fig. 8 to its position of Fig. 9 to thereby disengage the split nut 89 from its driving screw 56.
- 10 If desired, the flow of insulating powder from the hopper 34 to the feeding cylinder 38 may be shut off by means of the manual powder shut-off valve 29a.

15 It will be understood that when the sheath has been filled with the insulating material and the vibratory and centering devices have been released from the driving screw 76 and the flow of powder has been shut off, the terminal 12 will be disengaged from the rod 23. This operation may be facilitated by moving the centering device 71 above the connection between the terminal and the rod 23. The loaded unit may then be removed from the apparatus, and another heater assembly inserted in the machine for a loading operation. Then the centering and vibratory devices are lowered manually, and the lever 101 operated to start the next loading operation.

It is to be understood that a single machine
30 may be operated as has just been described or
that the machines may be arranged in any suit-
able number in a bank or battery. In the latter
case, the shaft 70 driving the feed gear 69 of the
various machines will extend through the bat-
35 tery and will be operated by a source of power
common to all the machines. It will also be
understood that a single source of power will
be used to drive all the vertical screws 76 through
their gear drives 76a.

40 Different lengths of sheaths within limits may be filled using the same pedestal 18, 19, etc. However, if the lengths of the units vary widely from that shown, pedestals of different and proper lengths will be used. Furthermore,
45 sheaths of different diameters may be loaded. To accommodate the machine to sheaths of different diameters it is merely necessary to replace the upper holding member 15 by a similar member provided with a recess 16 of the proper diameter and to use centralizing parts 72, 72a of proper size.

Important features of this invention are the provision of means for obtaining a steady flow of powder from the hopper 34 to the sheath, a uniform rise of the centralizing device 71 and the vibrator 86 so that movement of these members is synchronized with the rate of rise of the level of powder within the tube 11. Another important feature is the provision of a single manually operable lever 101 to effect the operation of the machine, and further, the automatic stop for the machine when the sheath has been loaded.

65 While I have shown a particular embodiment of my invention, it will be understood, of course, that I do not wish to be limited thereto since many modifications may be made, and I, therefore, contemplate by the appended claims to cover any such modifications as fall within the 70 true spirit and scope of my invention.

What I claim as new and desire to secure by Letters Patent of the United States is:

Letters Patent of the United States, is:

1. Apparatus for loading sheath wire heating units provided with a sheath, a resistance conductor within the sheath and insulating material,

within said sheath embedding said resistance conductor comprising means for feeding said insulating material into said sheath, means for regulating the feed of said insulating material into said sheath, guide means within said sheath engaging said resistance element to hold it in fixed spaced relation with said sheath and means for moving said guide means within said sheath at a regulated rate as said sheath is filled with said insulating material so as to support succeeding portions of said conductor in said spaced relation with said sheath until said portions are embedded by said insulating material.

2. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends of said resistance conductor substantially in the vertical center line of said sheath, means for feeding said powdered insulating material into said sheath, a centralizing guide member within said sheath engaging said helical resistance conductor to hold intermediate portions of said conductor substantially in said center line of said sheath, means for moving said guide member at a uniform predetermined rate from the lower to the upper end of said sheath and means for regulating the feed of said insulating material into said sheath in accordance with the rate of movement of said guide member so that the level of said insulating material in said sheath follows and is maintained at a predetermined position with reference to said guide member.

3. Apparatus for loading sheath wire heating units provided with a sheath, a resistance conductor within the sheath and insulating material 40 within said sheath embedding said resistance conductor comprising means for feeding said insulating material into said sheath, means for regulating the feed of said insulating material into said sheath, guide means within said sheath en- 45 gaging said resistance element to hold it in fixed spaced relation with said sheath, means for moving said guide means within said sheath at a regulated rate as said sheath is filled with said insulating material so as to support succeeding 50 portions of said conductor in said spaced relation with said sheath until said portions are embedded by said insulating material, and means imparting intermittent blows to said sheath progressively- 55 ly at a regulated rate along said sheath so as to compact said insulating material as it is added to said sheath.

4. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, means for moving said guide member at a uniform predetermined rate from the lower to the upper end of said sheath, means for regulating the feed of said insulating material into

said sheath so that the level of said insulating material in said sheath follows and is maintained a predetermined distance below said guide member, a vibratory device arranged to intermittently apply impacting blows to the external walls of said sheath so as to settle said insulating material in said sheath and means for moving said vibratory device from the lower to the upper end of said sheath at a regulated rate so that said 5 blows are always applied substantially at the rising level of said powdered insulating material in said sheath.

5. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends 10 of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, a screw, means for operating said screw, a nut for operating said guide member arranged 15 to engage said screw so as to be driven thereby and thereby move said guide member within said sheath, and means for engaging and disengaging 20 said nut with said screw.

6. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends 25 of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, a screw, means for operating said screw, a nut for operating said guide member arranged 30 to engage said screw so as to be driven thereby and thereby move said guide member within said sheath, and means for engaging and disengaging said nut with said screw.

7. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends 35 of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, a screw, means for operating said screw, a nut for operating said guide member arranged to engage said screw so as to be driven thereby and thereby move said guide member within said sheath, and means for engaging and disengaging said nut with said screw.

8. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends 40 of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, a screw, means for operating said screw, a nut for operating said guide member arranged to engage said screw so as to be driven thereby and thereby move said guide member within said sheath, and means for engaging and disengaging said nut with said screw.

9. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends 45 of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, a screw, means for operating said screw, a nut for operating said guide member arranged to engage said screw so as to be driven thereby and thereby move said guide member within said sheath, and means for engaging and disengaging said nut with said screw.

10. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends 50 of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, a screw, means for operating said screw, a nut for operating said guide member arranged to engage said screw so as to be driven thereby and thereby move said guide member within said sheath, and means for engaging and disengaging said nut with said screw.

11. Apparatus for loading sheath wire heating units provided with a sheath, a helical resist-

said insulating material into said sheath, means for regulating the rate of feed of said insulating material into said sheath, a vibratory device arranged to impart intermittently impacting blows to said sheath, a screw, means for operating said screw, a nut arranged to be driven by said screw, and an operable connection between said nut and said vibratory device whereby the latter is driven by said screw to progressively impart impacting blows along the length of said sheath.

12. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends of said resistance conductor substantially in the vertical center line of said sheath, means for feeding said powdered insulating material into said sheath, a centralizing guide member arranged to be fitted into said sheath so as to hold intermediate portions of said helical resistance conductor substantially in said center line of said sheath, a vibratory device arranged to apply impacting blows to the exterior walls of said sheath, a screw, means for operating said screw at a uniform rate, a split nut arranged to engage said screw and to be disengaged therefrom, means for engaging and disengaging said nut with said screw, a tubular member surrounding said screw connected to said nut so as to be driven thereby, means connecting said guide member and said tubular member so that said guide member is driven by said nut at a regulated rate in said sheath, and means connecting said vibratory device with said nut whereby said vibratory device is driven at a regulated rate along the exterior of said sheath.

13. Apparatus for loading sheath wire heating units provided with a sheath, a helical resistance conductor within said sheath and powdered heat conducting electrically insulating material within said sheath embedding said resistance conductor comprising means for supporting said sheath substantially in a vertical position, means securing the ends of said resistance conductor substantially in the vertical center line of said sheath, means for supplying said powdered insulating material to said sheath at a regulated rate, a guide member within said sheath arranged to engage said resistance conductor to hold the engaged portion substantially in said vertical center line, a vibratory device arranged to impart impacting blows intermittently to said sheath to compact said insulating material, a driving screw, a split nut arranged to engage and disengage said screw, driving connections between said nut and said guide member and between said nut and said vibratory device so that when said nut engages said screw said members connected with it are driven from the lower to the upper end of said sheath by said screw, means for driving said screw at a regulated uniform rate so that said guide member and said vibratory device move upwardly at approximately the same rate as the level of said insulating material rises in said sheath, a manually operable control device controlling said nut to engage it with said screw and means automatically releasing said nut from said screw when said guide member and said vibratory device reach approximately the upper end of said sheath.

14. Apparatus for loading sheath wire heating units provided with a sheath, a helical resist-

ance conductor within said sheath and powdered heat conducting electrically insulating material within said sheath embedding said resistance conductor comprising means for supporting said sheath substantially in a vertical position, means securing the ends of said resistance conductor substantially in the vertical center line of said sheath, means for supplying said powdered insulating material to said sheath at a regulated rate, a guide member within said sheath arranged to engage a portion of said resistance conductor to hold said portion substantially in said vertical center line, a vibratory device arranged to impart impacting blows intermittently to said sheath to compact said insulating material, a driving screw, a split nut arranged to engage and disengage said screw, a driving connection between said nut and said guide member and between said nut and said vibratory device so that when said nut engages said screw said members connected with it are driven from the lower to the upper end of said sheath by said screw, means for driving said screw at a uniform rate so that said guide member and said vibratory device move upwardly at approximately the same rate as the level of said insulating material rises in said sheath, a manually operable control device controlling said nut to engage it with said screw, means automatically releasing said nut from said screw when said guide member and said vibratory device reach approximately the upper end of said sheath, and means controlled by said manually operable member controlling the feed of said insulating material to said sheath.

35 12. Apparatus for loading sheath wire heating units provided with a sheath, a helical resistance conductor within said sheath and powdered heat conducting electrically insulating material within said sheath embedding said resistance conductor comprising means for supporting said sheath substantially in a vertical position, means securing the ends of said resistance conductor substantially in the vertical center line of said sheath, a hopper for holding said powdered insulating material, a chute for directing insulating material from said hopper into said sheath, a rotary conveyer between said hopper and said chute for conveying insulating material from said hopper to said chute at a uniform rate, a driving member for operating said conveyer at a substantially uniform rate, a clutch between said conveyer and said driving member, a manually operable lever arranged to effect the engagement of said clutch, a guide member within said sheath arranged to engage said resistance conductor to hold it substantially in said vertical center line, a vibratory device arranged to impart impacting blows intermittently to said sheath to compact said insulating material, a driving screw, a split nut arranged to engage and disengage said screw, a driving connection between said nut and said guide member and between said nut and said vibratory device so that when said nut engages said screw the members connected with it are driven from the lower to the upper ends of said sheath by said screw, means for driving said screw at a uniform regulated rate so that said guide member and said vibratory device move upwardly at approximately the same rate as the level of said insulating material rises in said sheath, means operated by said lever controlling said nut to engage it with said screw and means automatically releasing said nut from said screw when said guide member and vibratory device

reach approximately the upper end of said sheath.

13. Apparatus for loading sheath wire heating units provided with a sheath, a helical resistance conductor within said sheath and powdered heat conducting electrically insulating material within said sheath embedding said resistance conductor comprising means for supporting said sheath in an upright position, means for holding the ends of said resistance conductor substantially in the vertical center line of said sheath, means for feeding said powdered insulating material into said sheath at a regulated rate, a centralizing guide member arranged to be fitted into said sheath so as to hold intermediate portions of said helical resistance conductor substantially in said central line of said sheath, a vibratory device arranged to intermittently apply impacting blows to the external walls of said sheath so as to settle said insulating material in said sheath, means for moving said guide member and said vibratory device at a regulated rate from the lower to the upper end of said sheath, and means responsive to the operation of said guide means and said vibratory device controlling the rate of feed of said insulating material to said sheath.

14. Apparatus for loading sheath wire heating units provided with a sheath, a resistance conductor within said sheath and powdered heat conducting electrically insulating material within said sheath embedding said resistance conductor comprising means for supporting said sheath in an upright position, a hopper for storing said insulating material, a chute, a passageway between said hopper and said chute, means for feeding insulating material from said hopper to said chute at a regulated rate through said passageway, means mounting said chute for movement from a remote position with reference to said sheath to an operating position with reference to said sheath wherein insulating material fed to said chute is directed into said sheath, means associated with said chute for shutting off the flow of powder from said passageway into said chute when said chute is moved to said remote position and means for moving said chute between said positions.

15. Apparatus for loading sheath wire heating units provided with a sheath, a resistance conductor within said sheath and powdered heat conducting electrically insulating material within said sheath embedding said resistance conductor comprising means for supporting said sheath in an upright position, a hopper for storing said insulating material, a chute, a passageway between said hopper and said chute, means for feeding insulating material from said hopper to said chute at a regulated rate through said passageway, means mounting said chute for movement from a remote position with reference to said sheath and an operating position with reference to said sheath wherein insulating material fed to said chute is directed into said sheath, means associated with said chute for shutting off the flow of powder from said passageway into said chute when said chute is moved to said remote position, means for moving said chute between said positions, a latch for holding said chute in said operating position, a centralizing guide member arranged to be fitted into said sheath so as to engage said resistance conductor and hold said resistance conductor substantially in the center line of said sheath, means for moving said guide member at a predetermined

rate from the lower to the upper end of said sheath, a vibratory device arranged to intermittently apply impacting blows to the external walls of said sheath so as to settle said insulating material in said sheath, means for moving said vibratory device from the lower to the upper end of said sheath at a regulated rate, and means responsive to the operation of said vibratory device for releasing said latch when said vibratory device reaches substantially the upper end of said sheath.

16. Apparatus for loading sheath wire heating units provided with a sheath, a helical resistance conductor within said sheath and powdered heat conducting electrically insulating material withdrawn in said sheath embedding said resistance conductor comprising means for supporting said sheath substantially in a vertical position, means securing the ends of said resistance conductor substantially in the vertical center line of said sheath, a hopper for holding said powdered insulating material, a chute for directing insulating material from said hopper into said sheath, a rotary conveyer between said hopper and said chute for conveying insulating material from said hopper to said chute at a uniform rate, a driving member for operating said conveyer at a substantially uniform rate, a clutch between said conveyer and said driving member, a manually operable lever arranged to effect the engagement of said clutch, means mounting said chute for movement from a remote position with reference to said sheath and to an operative position with reference to said sheath wherein insulating material fed to said chute is directed into said sheath, means operably associated with said chute for shutting off the flow of powder from said passageway into said chute when said chute is moved to said remote position, means mechanically connecting said chute with said lever so that when said lever is operated to engage said clutch, said chute is moved to its operative position with reference to said sheath, a latch for locking said chute in said operative position, a guide member within said sheath arranged to engage said resistance conductor to hold it substantially in said vertical center line, a vibratory device arranged to impart impacting blows intermittently to said sheath to compact said insulating material, a driving screw, a split nut arranged to engage and disengage said screw, a driving connection between said nut and said guide member and between said nut and said vibratory device so that when said nut engages said screw said members connected with it are driven from the lower to the upper ends of said sheath by said screw, means for driving said screw at a uniform regulated rate so that said guide member and said vibratory device move upwardly at approximately the same rate as the level of said insulating material while it is being added to said sheath, means operated by said lever controlling said nut to engage it with said screw, means automatically releasing said nut from said screw when said guide member and vibratory device reach approximately the upper end of said sheath, and means responsive to the operation of said vibratory device for releasing said latch when said vibratory device reaches substantially the upper end of said sheath.

35

ALBERT H. SIMMONS.
